INSULATING STRUCTURE

Thomas S. Donnelly, Detroit, Mich.

Application October 13, 1941, Serial No. 414,769

6 Claims.

(Cl. 219—8)

My invention relates to a new and useful improvement in an insulating structure adapted primarily for use on electrode holders used in arc welding and similar operations. Among the types of electrode holders used is one in which there is a pair of separable jaws normally spring held in closed relation so as to grip an electrode therebetween. In order to spring these jaws apart a rockable stirrup is used through which one of the jaws is projected so that the base of the stirrup lies between the jaws and serves as a cam when the stirrup is rocked. Projecting outwardly from the upper side of the stirrup is a prong or rod whereby the stirrup may be rocked against the tension of the spring jaws to force the same apart. In some uses of electrode holders it is desirable that no metal parts be exposed and to accomplish this, insulation is resorted to. In the present structure the prong or rod is embraced by a tubular piece of insulating material formed from fibre, an asbestos composition or the like, the purposes being to insulate against electric conductivity and also against heat.

The present invention embodies a means for insulating the outer face of the side bars of the stirrup and the outer face of the top bar of the stirrup. Various means have been resorted to for insulating this stirrup and experience has shown that the insulation for the side bars and the top bar, because it is subjected to high heat, frequently is destroyed and has to be replaced.

The present invention has as its object a means of insulating a stirrup of this nature in such a manner that the insulation will be held in position and be readily and easily removable and replaceable.

Another object of the invention is the provision of L-shaped members each adapted for covering the outer face of one of the side bars and a portion of the top bar of the stirrup and provided with a notch for accommodating the outwardly projecting rod or prong.

Another object of the invention is the provision in an electrode holder, of means for insulating a stirrup of this kind in such a manner that the insulating material may be easily secured in position and prevented from undue movement while in use.

Another object of the invention is the provision in an electrode holder of an insulating member having a pair of angularly directed portions provided with openings formed therein.

Other objects will appear hereinafter.

The invention consists in the combination and arrangement of parts hereinafter described and

claimed and it is recognized that departures and variations may be made from the detail of structure without departing from the spirit of the invention and it is intended that such variations shall be embraced in claims forming a part hereof.

Forming a part of the specification is a drawing in which:

Fig. 1 is a side elevational view of an electrode holder showing the invention applied, with parts of the holder broken away and parts shown in section.

Fig. 2 is a sectional view taken on line 2—2 of Fig. 1.

Fig. 3 is a sectional view taken on line 3—3 of Fig. 1.

Fig. 4 is a perspective view of an insulating member.

Fig. 5 is a perspective view of the insulating member shown in Fig. 4, divided.

Fig. 6 is a view similar to Fig. 2 illustrating the undivided insulating member in use.

For the purposes of illustration I have indicated, in Fig. 1 an electrode holder on which the invention may be mounted. This holder comprises a pair of shank-forming portions 8 and 9 which are positioned with concave portions directed toward each other to provide a barrel or well in which the bared end 10 of the conductor 11 may be secured. Projecting outwardly from the forward end of the barrel sections are spring jaw-forming members 8' and 9', a bolt 12 being projected through these members for adjustment purposes. Mounted on the outer faces of the jaw-forming members 8' and 9' adjacent their ends are plates 13 and 14 of suitable insulating material. An insulating handle 15, formed from fibre or the like, is mounted in embracing relation on the shank-forming portions 8 and 9. The jaws are positioned in superimposed relation and normally held in close approach to each other so as to grip an electrode wire therebetween, the jaws being of sufficiently resilient material to accomplish this. In order to spring the jaws apart for insertion of the wire therebetween I provide a stirrup embodying the lower or bottom bar 16, the top bar 17 and the side bars 18 and 19. Projecting upwardly and angularly from the top bar 17 is a prong or rod 20 of spike-like structure, this rod being formed integral with the rest of the stirrup. As illustrated, one of the jaws 9' is extended through the stirrup so that the bottom bar 16 will, when the stirrup is rocked, operate as a cam for spreading the jaws apart as shown in Fig. 1, the jaws being illustrated in spread-apart position in Fig.

1 in full lines and in closed position in Fig. 1 in dotted lines. To insulate the outer face of the side bars 18 and 19 and top bar 17 I utilize a structure which may be U-shaped as shown in Fig. 4 or L-shaped as in Fig. 5. In order to provide the L-shaped structure in Fig. 5 it is but necessary to saw or otherwise cut the U-shaped structure of Fig. 4 centrally across the bight. This structure is formed from a strip of suitable insulating material such as fibre, asbestos composition or the like. Covering the outer face of the bar 18 is the leg 22 and the angularly turned portion 22' of this leg serves to engage and cover a portion of the outer face of the top bar 17. Covering the outer face of the side bar 18 is the leg 23 having the angularly turned portion 23' covering a portion of the outer face of the top bar 17, each of these portions 22' and 23' having formed in their opposing end faces a notch 24, so that as the jaws 22' and 23' are brought substantially into engagement with each other the opposed notches 24 will form an opening 24' through which the rod or prong 20 may project.

As shown in Fig. 4 the structure may be formed originally of U-shaped construction, the legs 22 and 23 each having openings 26 formed therein and the bight 25 of the U-shaped structure having opening 24' formed therein. By cutting this bight 25 diametrically of the opening 24' a pair of structures illustrated in Fig. 5 are thus formed. When placed in position as shown in Fig. 2 screws 27 are projected through openings 26 and threaded into the side bars 18 and 19 so that the structure is securely held in position. The structure illustrated in Fig. 4 may be mounted on the stirrup by projecting the prong or rod 20 through opening 24' and sliding the U-shaped structure downwardly onto the stirrup. When the screws 27 are secured in position a rocking of this U-shaped structure on the upper face of the bar 17 would be prevented. This is also the case when the L-shaped pieces in Fig. 5 are used.

It will be noted that the tube 28 which is formed of insulating material is inserted over and forms an extension of the prong or rod 20 to provide a handle or hand grip for applying the necessary pressure to rock the stirrup. It will be noted that the lower end of this tube 28 terminates in spaced relation to the outer face of the bar 17. The spacing of the lower end of the tube 28 from the outer face of the bar 17 is a distance substantially equal to the thickness of the portions 22' and 23' so as to normally engage the outer face thereof.

Thus the end of the tube 28, serves to prevent upward swinging or bending of the portions 22' and 23'.

In the use of an electrode holder of this type the members 22 and 23 are subjected to intense heat and frequently are burned off. They sometimes are damaged through contact with other objects. In the use of an electrode holder, only one of the members 22 or 23 would be directed toward the heat, depending upon the manner and custom of the welder in holding his electrode holder. Should one of the members 22 or 23 become damaged or burned so that it no longer functions as an insulating member for the bars 18 or 19, the retaining screw may be removed and, if the form shown in Fig. 4 is used, the bight 25 may be slit diametrically of the opening 24' thus permitting removal of the portion of the insulation which it has become necessary to replace. A section such as shown in Fig. 5 may then be

slipped into position and secured by the screw 27, the portion 23 sliding between the outer face of the bar 17 and the adjacent end face of the tube 28.

Thus, I have provided a means for insulating a stirrup of this kind whereby either side of the insulating means may be easily and quickly removed and replaced without necessitating a disturbance of the other side. I have also provided an insulating member having a portion insulating the outer faces of the side bar and a portion insulating the outer face of the top bar 17. When the portion shown in Fig. 5 is used the notch 24 serves as a means for resisting, through its engagement with the prong or rod 20, any tendency to twist or rock the insulating piece. The end of the tube 28 serves as a substantial cover for the split separating the pieces 22' and 23'.

It will be noted from Fig. 2 that these members 22 and 23 are extended beyond the end of the side bars 18 and 19 and thereby serve as additional protection from contact of foreign articles particularly metal with the lower jaw 8' at the location of the members 22 and 23. Experience has shown that this extension has desirable features although the members 22 and 23 may, if desired, be terminated flush with the outer face of the lower bar 16.

In this way I have provided a simple and effective means of insulating the stirrup in such a manner that the insulation may be readily removed and replaced.

What I claim as new is:

1. In combination with an electrode holder, a jaw rocking stirrup of the class described having oppositely disposed side bars and a top bar; means for insulating the outer face of said side bars and said top bar comprising a pair of L-shaped bodies secured to said stirrup, the leg of each of said bodies overlying and covering the outer face of said side bar and the balance of said bodies being extended inwardly toward each other for substantially covering the outer face of said top bar, the opposed faces of the ends of said bases of said L-shaped bodies having a recess formed therein, said bodies, when mounted on said stirrup, forming a substantially U-shaped structure; and means for securing either of said bodies on said stirrup independently of the other.
2. In combination with an electrode holder, a jaw rocking stirrup of the class described having oppositely disposed side bars and a top bar; insulating means for covering the outer faces of the said side bars embodying a pair of L-shaped members, the legs thereof overlying and covering the outer face of the side bars of said stirrup and the base thereof projecting inwardly of and covering a portion of the outer face of said top bar; and means for securing said L-shaped members on said stirrup each independently of the other.
3. In combination with an electrode holder, a jaw rocking stirrup of the class described having oppositely disposed side bars and a top bar and provided with a handle forming member projecting outwardly from said top bar, means for insulating the outer faces of said side bars and said top bar comprising a pair of L-shaped members of insulating material one portion of each of said members overlying and covering the outer face of a side bar and the other portion of each of said members being directed inwardly to overlie and cover the outer face of said top bar; and means for securing said members on said stirrup each independently of the other.

4. In combination with an electrode holder, a jaw rocking stirrup of the class described having oppositely disposed side bars and a top bar and provided with a handle forming member projecting outwardly from said top bar, means for insulating the outer faces of said side bars and said top bar comprising a pair of L-shaped members of insulating material one portion of each of said members overlying and covering the outer face of a side bar and the other portion of each of said members being directed inwardly to overlie and cover the outer face of said top bar, the opposed faces of said portions of said L-shaped members which overlie said top bar having a notch formed therein for partially embracing said handle-forming member; and means for securing said members on said stirrup each independently of the other.

5. In combination with an electrode holder, a jaw rocking stirrup of the class described having oppositely disposed side bars, a top bar and a handle-forming member projecting outwardly from said top bar, means for insulating said stirrup comprising a strip of insulating material bent between its ends to provide a substantially U-shaped member embracing said stir-

rup, the bight of the U-shaped member covering the outer face of said top bar and the legs of said member covering the outer face of said side bars, said bight having an opening formed centrally therein for reception of said handle-forming member; and a tube mounted on said handle forming member in embracing relation and terminating at one end substantially in engagement with the outer face of the bight of said U-shaped member for retaining the same in close relation to the outer face of said top bar.

6. In an electrode holder, a jaw rocking stirrup of the class described having oppositely disposed side bars, a top bar and a handle-forming member projecting outwardly from the top bar, means for insulating the stirrup comprising a strip of insulating material bent between its ends to provide angularly extending portions overlying and covering the outer face of the side and top bars of the stirrup, and a tube of insulating material extending over the handle member and embracing the outer face of one of the angularly extending portions of the insulation strip to retain the same in close relation to the outer face of the top bar of the stirrup.

THOS. S. DONNELLY.
